DRYING FRAME FOR PETTICOATS AND SKIRTS

Lola L. Sund, Omaha, Nebr.

Application April 22, 1957, Serial No. 654,271

7 Claims. (Cl. 223—69)

This invention relates to drying frames and more particularly it is an object to provide a drying frame for petticoats.

As the purpose of a petticoat is to hold a skirt in an extended position, it is desirable that a petticoat be dried after laundering in such a manner that it dries in substantially the same shape that it will be when it is used.

It is therefore an object to provide a petticoat drying frame which is adapted to hold the petticoat in the same shape as it is when it is worn whereby the petticoat will tend to stand out away from the body of the wearer and also whereby undue wrinkling of the material is prevented.

Other and further objects and advantages of the present invention will be apparent from the following detailed description, drawings and claims, the scope of the invention not being limited to the drawings as the drawings are only for the purpose of illustrating a way in which the principle of this invention can be applied.

Other embodiments of the invention utilizing the same or equivalent principles may be used and structural changes may be made as desired by those skilled in the art without departing from the present invention and the purview of the appended claims.

In the drawings:

Figure 1 is a side elevation of the drying frame of this invention shown with a petticoat held thereon;

Figure 2 is a perspective view of the drying frame with a petticoat in a position for drying thereon and with a portion of the petticoat broken away for clarity of illustration, and with the standard removed from a supporting base;

Figure 3 is a sectional view showing a rib of the drying frame and portions of associated parts;

Figure 4 is a perspective view of the base for the drying frame;

Figure 5 is a sectional view showing a cross section through one of the ribs of the frame and illustrating the pivotal connection between one of the braces and the associated rib; and

Figure 6 is a view taken on line 6—6 of Figure 3 with the rib omitted and showing the opening for a rib in the lower portion of one of the handles of a spring clip for holding the edge of a garment.

Referring to Figure 1, the drying device of this invention includes a base 10 which is provided with an aperture 12 for receiving a shaft or standard 14 which is normally vertically disposed.

A collar 16 is slidably mounted on the standard 14, and the collar has many braces 20 pivotally attached to it in such a fashion that each brace 20 is adapted to pivot in a plane disposed radially with respect to the standard 14. The details of the attachment of the braces 20 to the collar 16 are not shown for the reason that they are the same as used in an umbrella frame.

The braces 20 extend upwardly to sleeves or fittings 22 which are themselves rigidly attached to elongated ribs 24. The fittings 22 are disposed about and are suitably

2

rigidly secured to the ribs 24, as best seen in Figure 5. Each rib 24 is hollow on its inner side, as best seen at 26, and is open on its inner side receiving the upper end of the respective brace 20 thereinto. The fitting 22 has inwardly extending nibs 30 on its inner side and these extend into apertures 34 in the sides of the respective braces 20, each brace 20 being also of U-shape similarly to the ribs 24.

The construction, shown in Figure 5 and just described, is conventional in umbrella frames.

The ribs 24 are pivotally secured to a stationary sleeve or mounting 40 which is itself rigidly attached to the standard 14.

As best seen in Figure 3, the stationary sleeve 40 includes an upper flange 42 and a lower group of fingers 44. The ribs 24 extend upwardly to positions between the upper flange and lower group of fingers and are pivotally attached to the sleeve 40 by means of a wire 50 which extends around the sleeve 40 in a manner conventional in umbrella constructions. Only a portion of the wire 50 is shown in Figure 3 for clarity of illustration.

As thus described, it will be seen that the ribs 24 swing upwardly and downwardly in planes radially disposed with respect to the standard 14. The lower ends of the ribs 24 are free to swing.

Along the standard 14 are stops 55 which are spaced apart along the standard 14 to hold the collar 16 in various positions for holding the ribs 24 different distances outwardly from the standard 14. The collar 16 is urged downwardly against the stops 55 by the weight of the ribs and braces with a garment thereon.

In accordance with this invention a first group of spring clips or holders 60 are placed at one end of each of the ribs, as best seen at the bottom ends of the ribs in Figures 2 and 3.

The holders 60 are adapted to be attached to the lower edge of a petticoat 62 when disposed over the ribs in Figures 1 and 2. The holders or clips 60 are preferably of a spring-grip type having two gripping jaws 66 and 68 which are adapted to be urged toward a clamping position by a spring 70. Teeth can be arranged, as seen at 72, on certain ends of the jaws 66 and 68 for gripping the petticoat.

The holders 60 can be urged into a releasing position by finger-engagable portions 76 to form a clip of conventional design, as best seen in Figure 3.

In accordance with this invention an aperture 80 is provided through one of the portions 76 of the clip and the aperture 80 is of a size larger than the respective rib 24 which it receives. The portion 76 of the clip which has the aperture 80 in it can be regarded in a sense referred to in claims hereinafter as an attachment member 76 for attaching each of the holders 60 to a respective rib 24.

The arrangement of the aperture 80, its size, and the size of the rib 24 is such that when the holders 60 are attached to a petticoat held on the drying device and when the petticoat is stretched so as to pull on the holder 60, then the walls of the aperture 80 become snubbed against the ribs whereby the attachment members 76, which are preferably portions 76 of the clip, are prevented from sliding along the ribs 24.

The construction is also such that when there is no tension on the holder 60 the attachment members are free to slide along the ribs 24 for ease of adjustment of their position.

The first group of holders 60 are prevented from falling off of the ribs 24 by any suitable means such as retainers 90 which are flexible spheres of plastic or otherwise having openings 92 therethrough, through which a large tip 94, conventionally found on umbrellas, can be inserted.

The apertures 80 are each of a particular shape, as best seen in Figure 6. The upper end of each aperture 81 is rounded and the aperture has vertical sides 82 which are adapted to closely fit certain vertical sides 98 of the ribs 24. The ribs 24 preferably have rounded upper sides 99, such construction being conventional in umbrella frames.

The aperture 80 is formed with a horizontal lower surface 84 although this and the rounded top 81 may be of any suitable shape.

It is very important that the sides 82 of the aperture 80 fit very closely to the ribs 24 or that the sides 82 be spaced from the sides 98 of the ribs 24 so as to prevent the holder or clip 60 from rotating about the rib for otherwise the holder 60 will tend to slide against the brace 20 when a frame is held up-side-down and can come into a position so as to interfere with the closing of the umbrella frame.

The ribs 20 are of non-round construction and the openings or apertures 80 are cooperatively shaped with respect thereto as seen in Figure 6, and also slightly larger than the cross-sectional shape of the ribs so as to permit a slight tilting action of the clips on the ribs whereby the clips grip the ribs in adjusted positions at times when the clips are attached to a garment which is stretched in such a way as to pull on the clips whereby the walls of said openings bind on the respective ribs. The non-round shape of the ribs and complementary or at least cooperative shape of the respective opening or aperture 80 is adapted to prevent the clips from rotating around the ribs undesirably.

Referring now to Figures 1 and 3 it will be seen that this invention further includes a second group of holders 100 disposed at the upper ends of the ribs 24 for attachment to the upper edge of the petticoat 62. The upper holds or clips 100 are preferably also of a type which have outer jaws 104 which clamp together under the urging of a spring, a portion of which latter can be seen at 106.

The holder or clamp 100 has handle portions 108 which are adapted to be pressed together to open the jaws 104. One of the handle portions 108 has an aperture therethrough, seen only at dotted lines at 110 in Figure 3. The aperture 110 is identical to the aperture 80 of the holder 60 so as to permit the holder 100 to also slide up and down the rib when desired, to become snubbed against the respective rib when clipped to the upper edge of the petticoat, but not to twist or rotate into a position underneath the respective rib 24 as the latter action would permit the holder 100 to interfere with the respective brace 20 preventing the proper closing of the frame.

The aperture or opening 80 of the holder 60 and the aperture or opening 110 of the holder 100 are complementary in shape to the outer configuration of the ribs and slightly larger than the ribs to permit a slight tilting of the clip as it sits astride the ribs.

The lower handle portion 108 of the holder or clip 100 can be regarded in a sense referred to in the claims hereinafter as an attachment member for attaching the respective holder 100 to a respective rib 24.

In operation it will be seen that the petticoat 62 can be held for drying in the shape in which it is worn by pushing upwardly on the collar 16, permitting the collar 16 to assume a suitable position above a selected one of the stops 55.

The petticoat can then be left to dry with its standard 14 supported on the base 10 or else with its standard 14 held to a clothesline wire or the like by a convenient clip 120 attached to the upper end of the standard 14.

As thus described it will be seen that this invention fulfills the objectives hereinabove set forth.

From the foregoing description, it is thought to be obvious that a drying frame for petticoats and skirts constructed in accordance with my invention is particularly well adapted for use, by reason of the convenience and

facility with which it may be assembled and operated, and it will also be obvious that my invention is susceptible of some change and modification without departing from the principles and spirit thereof, and for this reason I do not wish to be understood as limiting myself to the precise arrangement and formation of the several parts herein shown in carrying out my invention in practice, except as claimed.

I claim:

1. A garment drying rack comprising an elongated standard, a stationary member positioned on the upper end of the standard, ribs pivotally mounted in the stationary member and positioned to extend longitudinally of the standard, a pair of opposed material gripping clips on each of the ribs and positioned inwardly from the ends thereof, the clips having openings therein through which the ribs extend and the openings being complementary in shape to the outer configuration of the ribs and slightly larger than the ribs to permit a slight tilting of the clips as they sit astride the ribs, sleeves mounted on the ribs, a sliding collar positioned on the standard, braces pivotally connected to the sliding collar and also pivotally connected to the sleeves on the ribs, and latching means on the standard for retaining the sliding collar in operative positions for retaining the ribs in extended positions.

2. In a garment drying rack, the combination which comprises an elongated shaft, a stationary member on the upper end of the shaft, ribs pivotally mounted in the stationary member, sleeves mounted on the ribs, a sliding collar positioned on the shaft, braces pivotally connected at one of the ends thereof to the sliding collar and positioned with opposite ends thereof pivotally connected to the sleeves on the ribs, means for releasably maintaining said collar in a desired position on said shaft such that said ribs are maintained in positions inclining outwardly from said shaft a pair of clips slidably mounted on each of the ribs, the clips each having a pair of opposed jaws, the jaws of each clip of a rib being disposed opposite and facing the jaws of the other clip of the same rib respectively, said clips having means thereon provided with openings therethrough through which the ribs extend, the walls of said openings being cooperative in shape to the outer configuration of the ribs and being slightly larger than the ribs, and said means having said openings therethrough being so disposed with respect to said jaws that a pulling on said jaws causes a tilting of said means with respect to said ribs respectively whereby the walls of said openings grip the ribs for holding said clips in adjusted positions so long as there is a pulling on the jaws of said clips so that a garment gripped in opposed clips and stretched so as to tension said clips will cause said clips to grip said ribs.

3. In a garment drying rack, the combination which comprises an elongated shaft, a stationary member on the upper end of the shaft, ribs pivotally mounted in the stationary member, a sliding collar positioned on the shaft, braces pivotally connected at one of the ends thereof to the sliding collar and positioned with opposite ends thereof pivotally connected to the ribs at a substantial distance from each end thereof, means for releasably maintaining said collar in a desired position on said shaft such that said ribs are maintained in positions including outwardly from said shaft, a pair of clips having openings therethrough slidably mounted on each of the ribs with each rib disposed through each respective clip opening, each of said clips having a pair of opposed jaws, means of urging the jaws of each clip toward each other for gripping a garment, the jaws of each clip of a pair being disposed facing one another respectively, means attaching one clip of each pair of said clips at one end of each rib, means adjustably attaching the other clip of each pair of said clips to the other end of each rib to said ribs in a manner whereby they can be placed in selective positions for putting tension on a garment disposed between a pair of clips and maintained in a selected position for

holding the garment in stretched position during drying, the walls of said openings being cooperative in shape to the outer configuration of the ribs and slightly larger than the ribs to permit a slight tilting action of the clips on the ribs whereby the clips grip the ribs in adjusted positions.

4. A combination of claim 3 further including the provision of means on the lower end of the ribs for preventing accidental separation of the clips from the ribs.

5. The combination of claim 3 further including a base having an opening therein, the opening of the base being formed to receive an end of said shaft whereby the base supports the shaft in an upright position.

6. The combination of claim 3 which includes a spring hook attached to the end of said shaft for facilitating the suspension of said shaft.

7. The combination defined in claim 3 in which said ribs are of non-round shape in cross section and in which the wall of said openings is cooperatively shaped with respect to said ribs so as to prevent said clips from undesirably rotating around said ribs.
